(57) **CLAIM**

The ornamental design for a bicycle lamp, as shown and described.

DESCRIPTION

FIG. 1 is a front, right and top perspective view of a bicycle lamp showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded view of FIG. 1; and,

FIG. 10 is an exploded view of FIG. 2.

The broken lines shown in the figures are for the purpose of illustrating portions of the bicycle lamp that forms no part of the claimed design.
